GROUND ROD

William J. McIlvane, Bellerose, N. Y., assignor to
 Bridgeport Brass Company, Bridgeport, Conn.,
 a corporation of Connecticut

Application August 24, 1932, Serial No. 630,202

5 Claims. (Cl. 173—31)

This invention relates to ground rods used for grounding electrical apparatus. Customarily, such rods are driven into the earth to provide electrical grounds for lightning arresters, radio circuits, transformer cases, and other electrical apparatus and equipment.

In providing a ground rod or ground electrode which would be long-lived and would not be subject to attack by corrosion, it has been considered necessary in many cases to make the rod itself of copper, or steel covered with copper. With such a rod, it was possible to connect the copper lead wires to the rod body having an outer surface of copper without causing corrosion due to galvanic action between the rod and the wires or parts thereof. However, copper rods do not have the necessary rigidity to be driven into hard earth, and steel rods covered with copper have been somewhat difficult or expensive to produce.

One of the objects of my invention is to provide a construction which permits the employment of a rod proper made of wrought iron, so that the rod may be sufficiently strong and rigid and may at the same time be relatively inexpensive and have very satisfactory resistance to underground corrosion, which is a condition realized very effectively when the rod is made of puddled iron, for example. However, my improvements are not limited to the use of wrought iron, as the rod proper may be made of copper-bearing steel or other alloy steel or iron which resists underground corrosion.

Another object of my invention is to provide a non-corroding construction in which the lead wire or wires can be effectively clamped to the rod by a releasable mechanical clamp of simple nature. It is intended to provide a device which is very convenient in use and yet relatively inexpensive.

Another object is to provide means for connecting copper or other non-ferrous ground wires to ferrous ground rods in a simple and efficient manner and with the avoidance of galvanic corrosion.

To these and other ends, the invention consists in the novel features and combinations of parts to be hereinafter described and claimed.

In the drawing:

Fig. 1 is a side elevation of a ground rod constructed in accordance with my invention;

Fig. 2 is a top plan view of the parts shown in Fig. 1;

Fig. 3 is a side elevation of a modified structure in which approximately rectangular wire clamping plates are employed;

Fig. 4 is a top plan view of the parts shown in Fig. 3;

Fig. 5 is an edge view of the structure shown in Fig. 3;

Fig. 4a shows the clamping block illustrated in Fig. 4 but with the transverse bolt and side clamping plates omitted and with a lead wire clamped to the front edge portion of the block;

Fig. 6 is a side elevation of a still further modified form; and

Fig. 7 is a top plan view of the parts shown in Fig. 6.

It is understood from what has been said above that in the practice of my invention, the ground rod proper is preferably constructed of wrought iron or other ferrous material; that the lead wire or wires are preferably made of copper or other non-ferrous metal; and that it is aimed to provide a structure for connecting the lead wire or wires to the rod in a manner which is simple and convenient and which overcomes the setting up of galvanic action in the structure.

In the form shown in Figs. 1 and 2, the ground rod proper, which is indicated at 10, may be assumed to be a long pointed rod of wrought iron. 25 To this rod is connected a substantially rectangular clamping block 11 of copper, by means of which the copper lead wires 12 are connected electrically with the iron rod. The copper block 11 is preferably grooved at one side, as indicated at 13, so as to conform to the curvature of the cylindrical electrode body, and where the block conforms to the electrode body, it is secured thereto by a corrosion-proof joint, such as provided by welding, brazing, soldering, or otherwise permanently securing the block to the rod. In the particular form shown in Figs. 1 and 2, ground wires 12 may be attached to the block at opposite sides thereof so that wires in multiple can be connected to ground. In this structure, as illustrated, two 30 grooves 14 of semicircular cross section extend parallel to each other at each side face of the block throughout the height of the block, and between these grooves is located a bore 15 to receive a clamping bolt 16 having a head 17 on one end and a nut 18 engaging threads on the opposite end of the bolt shank. Round copper washers 19 may be employed for clamping the wires to the faces of the block in an obvious manner.

In the form shown in Figs. 3, 4, 4a and 5, the structure is modified in some particulars. In this instance, the block 20, instead of having grooved side faces, has plain flat side faces, and wires are clamped against it and held against

lateral dislocation by substantially rectangular clamping plates 21 of copper having grooved side portions 22 which engage the lead wires and in turn are engaged by round copper washers 23. 5 One of the washers 23 is located beneath the head 11a of bolt 16a, and the other washer is located in engagement with a nut 18a engaging the threaded shank of bolt 16a.

In this second form, a lead wire may be secured to the front or outer edge of the clamping block, if this is desired. In such case, the removable clamping devices shown in Fig. 4 are taken off the block, and a small clamping plate 24 is secured in position at the front face of the 10 block by the small bolt 25 having a threaded shank engaging a threaded socket 26 in the clamping block, as shown in Fig. 4a. In this case the lead wire 12a is held in place by plate 24 in a groove 27 at the front edge of the block, as 15 shown more particularly in Fig. 5.

It will be understood that in the constructions so far described, the copper or similar non-ferrous clamping block is attached to the ferrous rod in a manner which prevents the setting up of 20 galvanic action between the block and the rod; and that inasmuch as the lead wire or wires and the block are made of the same metal, a releasable mechanical clamp may be used between them without causing galvanic action to be set up between the block and the wire or wires.

In the modified form shown in Figs. 6 and 7, the attaching block instead of being made entirely of non-ferrous metal is constructed partly of ferrous metal. Inasmuch as that part which 25 contacts with rod 10 is made of the same material as said rod, it can have a releasable clamping engagement with said rod. Thus, in the particular form shown, the ferrous attaching plate 28 has formed integral with it a ferrous 30 sleeve member 29 adapted to be slid along rod 10 and to be held in the desired position thereon by means of ferrous set screw 30. At opposite faces of plate 28, non-ferrous plates 31 are secured thereto in a manner which provides 35 against the setting up of galvanic action, for example, by welding, brazing or soldering members 31 to member 28, thus forming a composite clamping block. The members 31 are provided with grooves 32 similar to the grooves 40 14 previously described, and the non-ferrous ground wires 12b are releasably held in these grooves by means similar to those described with reference to the structure shown in Figs. 1 and 45 2. The structure shown in Figs. 6 and 7 is, in fact, similar to that shown in Figs. 1 and 2, the principal difference being that in the former arrangement a ferrous supporting frame for the 50 clamping block is employed, such frame having releasable mechanical engagement with the body 55 of the electrode.

While I have illustrated and described several embodiments of my invention, I have not attempted to describe all of the different forms which may be taken by the invention without 60 departure from the principles of my invention as defined in the claims.

What I claim is:

1. In a device for connecting electrical apparatus to ground, the combination of a ground 65 rod body adapted to be driven into the ground, said body being made of ferrous material and resistant to bending, a clamping block located adjacent the upper end of the rod body and extending parallel to said body in the plane thereof and presented edgewise to said body and

curved to conform to the periphery thereof, said block having at the side face thereof a non-ferrous surface adapted to be engaged by ground wires for preventing electrolysis, means of connection between the edge portion only of said block and the rod body for securing the block to the rod body in rigid relation thereto, a clamping member of non-ferrous material located at one of the side faces of said block and adapted to clamp ground wires against said block, and a bolt extending into said block and clamping member for holding said clamping member in clamping relation to the wires. 5

2. In a device for connecting electrical apparatus to ground, the combination of a ground rod body adapted to be driven into the ground, a clamping block located adjacent the upper end of the rod body and extending parallel to said body in the plane thereof and presented edgewise to said body and shaped to conform to the periphery thereof, said block having at the side face thereof a surface of a different metal from that of the rod body adapted to be engaged by ground wires for preventing electrolysis, means of connection between the edge portion only of said block and the rod body for securing the block to the rod body in rigid relation thereto, a clamping member located at one of the side faces of said block and adapted to clamp ground wires against said block, and a bolt extending 10 into said block and clamping member for holding said clamping member in clamping relation to the wires. 20

3. In a device for connecting electrical apparatus to ground, the combination of a solid ground 25 rod of round cross section adapted to be driven into the ground, a substantially rectangular clamping block of a thickness approximating the diameter of the rod body located adjacent the upper end of the rod body and presented edgewise thereto so as to lie in the plane of the rod body, said block being in abutting relation to the rod body and curved to conform to the periphery thereof, said block having side faces of a different metal from that of the ground rod body 30 adapted to be engaged by ground wires, means for securing the block rigidly to the rod body, said block having a hole extending horizontally there-through between the rod body and the outer edge of said block, clamping members at the side faces 35 of said block, and a bolt passing through said hole for holding said clamping members in clamping relation to said block, the clamping parts intermediate the bolt and the rod body being provided with vertical wire-receiving grooves located at the side faces of the block and there being similar wire-receiving grooves at that side of the bolt which is remote from the rod body. 45

4. In a device for connecting electrical conductors to ground, the combination of a solid continuous ground rod body adapted to be driven into the ground and of substantially uniform round cross-section throughout the major part of its length, a clamping block of substantially rectangular shape extending parallel to the rod 50 body and presented edgewise thereto so as to lie in the plane of said body, said block being of a thickness approximating the diameter of the rod body and having a curved edge portion presented and conforming to the rod body, means 55 of integral connection between the curved edge of said block and said rod body whereby said block is rigidly and intimately connected with said body, a side face of said block being adapted to engage one or more electrical conductors and 60

being of a different metal from said ground rod body and of a similar metal to the conductors, for preventing electrolysis, a clamping member located at said side face of said block and adapted to clamp the conductors against said face, and a bolt in said block and said clamping member for holding said clamping member in clamping relation to the conductors.

5. In a ground rod structure, a ground rod body 10 of ferrous material and of solid round cross-section, a non-ferrous clamping block substantially rectangular in shape located adjacent the upper end of the rod body and extending parallel to said body and presented edgewise thereto so as 15 to lie in the plane thereof, said block being of a thickness approximating the diameter of the rod

body and having a curved edge portion presented to the rod body, means of intimate connection between the curved edge portion of said block and the rod body for securing the block to the rod body in rigid integral relation thereto, clamping members of non-ferrous material at the side faces of said block, and a bolt extending through a hole in said block and adapted to hold the clamping members in clamping relation to vertical wires interposed between the clamping members and the block, the clamping portions being provided with vertical wire-receiving grooves, certain of said grooves being between the bolt and the rod body and others being at the remote side of the bolt.

WILLIAM J. McILVANE.
